ELECTRON DISCHARGE DEVICE

Hampton Jennings Dailey, Bloomfield, N. J., assignor to Westinghouse Electric & Manufacturing Company, East Pittsburgh, Pa., a corporation of Pennsylvania

Application October 9, 1941, Serial No. 414,227

17 Claims. (Cl. 250—27.5)

This invention relates to electron discharge devices and particularly to means and methods of outgassing the grid forming an integral part of such device.

In the prior art, outgassing of a grid has been accomplished in one of several ways. For instance, the grid has been rendered incandescent by means of an induction current applied thereto while the electron discharge device is in the process of being evacuated. Such a method has certain drawbacks, amongst which may be mentioned the difficult or even the impossibility of induction-igniting the grid where the anode of low resistance material, such as copper, forms part of or forms the entire envelope containing the other triode electrodes. Another method of outgassing the grid has been to pass a heating current through the grid wires and thereby render those wires incandescent while the discharge device is on the exhaust machine. This again is unsatisfactory or impossible in actual practice in many instances, particularly when the grid has such form that a continuous circuit is disrupted by presence of supporting wires or posts or other bracing means at intervals along the length of the grid wire.

A further method of outgassing a grid employed in the prior art has been the use of electron bombardment obtained by heating the filament of the triode and at the same time applying a positive potential to the grid. This method likewise has its drawbacks, where presence of close grid-to-filament spacings requires relatively heavy currents at low voltages, which is detrimental to filament emission.

An object of the present invention is to devise a means and method of outgassing a grid overcoming the difficulties encountered by prior art methods.

A further object of the invention is to outgas the grid of triode electrodes without detriment to the other electrodes of such triode.

A further object of the invention is to provide means and method of outgassing a grid and in doing so to avoid excessive ion bombardment of the triode cathode.

A still further object of the invention is to provide a means and method available to electron discharge devices utilizing metal containers or other shielding structure around the grid.

Still further objects of the invention will appear to those skilled in the art as the description progresses, both by direct statement thereof and by implication from the context.

In the accompanying drawing, wherein like

numerals of reference indicate similar parts throughout the several views, and wherein preferred embodiments of the invention are disclosed by way of example;

Figure 1 is a view partially in elevation and partially in longitudinal section showing an electron discharge device, inclusive of its envelope, embodying the present invention in its preferred construction;

Figure 2 is a cross-sectional view on line II—II of Fig. 1;

Figure 3 is a view similar to Figure 1 but of a somewhat diagrammatic nature, for indicating the preferred electric circuit connections to the several electrodes and fabricating filament; and

Figure 4 is a view similar to Figure 3 showing a modified arrangement of circuits.

In the specific embodiment of the invention illustrated in said drawing, a part of a triode electronic discharge device generally identified as a transmitting tube, is depicted exemplifying the invention as part thereof. It should be understood, however, at the outset, that the invention is applicable to other electronic devices than the particular transmitting tube here selected for illustrative purposes.

The specific tube shown comprises a glass or other ceramic bowl 10, here represented as part of an evacuated envelope, and as also constituting the base portion for the device, for which purpose it is equipped with appropriate prongs 11 protruding from the bottom thereof. These prongs are each preferably unified with appropriate posts, such as 12, 13, and 14 shown in

Fig. 1, extending upwardly within the interior of said bowl or base portion 10. At the upper rim of the bowl portion 10, there is sealed into the glass or other ceramic a featheredge of a connecting ring-like portion 15 to a metal upper

portion which in part also constitutes the triode anode 16. A part of the anode proper is shown re-entrant with respect to the connecting rim or ring portion 15, thereby providing an annular upwardly opening exterior groove 17 serviceable in connection with cooling the anode in use.

Within the triode anode 16, spaced in parallelism to the same, is a bird-cage dome-like triode grid 18 providing a plurality of similar strands 19 in generally vertical planes, evenly distributed circumferentially and providing lower portions which are parallel to each other and upper portions which curve upwardly inward to a common vortex to obtain the dome-like contour of grid. Said grid is also shown as having a helically wound wire 20, each point of crossing

of which with the strands 19, is spot welded or otherwise secured, to constitute the strands and helically wound wire a unitary grid structure. The lower ends of the several strands 19 are secured to a horizontally disposed plate 21, as by screw and nut means 22 shown. Said plate is provided with a central opening 23 therein for passage of other terminal connections and posts therethrough, and is also provided with a peripheral rim or skirt at its edge for obtaining desired rigidity. A plurality of posts, of which posts 12 are representative, support said plate from the bowl and provide electrical connection from the said plate to one or more of the prongs depending from and sealed with respect to the bowl.

The triode filament designated generally by reference numeral 24 comprises a plurality of strands the major portions of which are parallel and together constitute a cylindrical assembly. The assembly provides a plurality of groups of strands wherein the strands of the groups are in electrical series to the source of current supply. Other like groups are in parallel to each other although the strands of each group are in electrical series within the group. A maximum electron emitting surface area for copious flow of electrons is thus provided with minimum current consumption.

In the fabrication of the triode filament assembly 24, a plurality of generally parallel spacer members are provided, namely, two next the bottoms of the strands of which the lowermost one is designated by numeral 25 and is situated horizontally or transverse to the filament strands. Physically and electrically spaced a short distance above this lower spacer member 25, and parallel thereto, is a second spacer member 26. These two spacer members are connected to opposite poles of the source of filament current supply, as indicated. Preferably, also, these spacer members are of plate formation, the lowermost one, 25, by its central aperture 25' permitting free passage therethrough without contact, of post 13 the upper end of which is electrically and physically secured to the next or second plate-like spacer member 26. This post 13 represents one lead-in means for the supply current to the filament and also passes through aperture or central opening 23 in plate 21 without electrical contact therewith. The lower spacer member 25 is supported by welding, brazing or otherwise securing the same physically upon upper ends of connector posts 28, 28 in turn secured near the apex of an A-bracket 29 horizontally disposed below and parallel to plate 21, with the legs of said bracket secured upon the tops of posts 14 and forming therewith electrical circuit from the filament to the other pole of the source of current supply.

Within the dome-like confines of the triode filament, is situated a temporary or fabricating filament, designated in Figures 1 to 3 by reference numeral 30 and in Figure 4 by reference numeral 30'. Said fabricating filament may be any one of various possible shapes, and by way of illustration an elongated spiral configuration therefor has been selected. The upper end of said fabricating filament is shown attached electrically and physically to the upper end of a metallic post 31 projecting upwardly and axially within the assembly of the triode electrodes, namely, the triode filament, grid and anode herefore described. Said post 31 is shown integral

with the upper or second spacer member 26 of the pair of spacers next the lower part of the triode electrodes, and stops short of the dome-portion of the innermost one of said electrodes. The several convolutions of the spiral formation of said fabricating filament are around said post but are out of contact therefrom. The lower end of the said fabricating filament is suitably attached both for purposes of physically positioning the same and for completing the electrical circuit. Filaments 24, 30 and 30' are all electron emissive when rendered incandescent by current flow therein.

As shown in Figures 1 to 3, the said lower end of the fabricating filament is secured, as by welding, to a lead-in connection 32 shown sealed through the glass base portion 10 with a sealing bead 33 and passing upwardly between the legs of A-bracket 29, upwardly through opening 23 in plate 21, and upwardly through appropriate openings in spacer members 25, 26 so as to avoid electrical contact with any of said parts. Exciting circuit for this fabricating filament accordingly follows a path through connection 32, filament 30, post 31, and appropriate prong 11 therefrom.

In the construction of Figure 4, fabricating filament 30' is attached in electrical parallel to triode filament 24 so that excitation of the fabricating filament will be obtained by filament current applied to the usual filament terminals. In this instance, however, the resistance gradient of the fabricating filament is such that the fabricating filament becomes ignited or electron emissive with application of lower current applied thereto than required to render the triode filament emissive. A current strong enough to render the triode filament incandescent and emissive will be so strong that it will burn out the fabricating filament, thereby rendering the fabricating filament inoperative thenceforth.

In process of fabrication, fabricating filament 30 in the preferred construction, is rendered incandescent and electron emissive during fabrication of the electron discharge device while the same is on exhaust. At such time, a positive potential is also applied to the grid so it will act as an anode, and the triode filament will act as a grid. This will result in a high voltage drop and a low current may be utilized to give an electronic bombardment of the grid but without subjecting the triode filament to detrimental ion bombardment during exhaust. After sealing off, the fabricating filament is no longer required, and the connection of exterior current supply to connection 32 is disrupted. If desired, said connection 32 may be sealed over at the place where it comes through the glass part of the envelope. Addition of a sealing nipple 33' has been indicated in dotted lines in Figure 1.

In constructing the device by use of the arrangement of Figure 4, while the device is being evacuated, a current is applied to the filament leads of intensity sufficient to cause the fabricating filament 30' to become incandescent and electron emissive, but not sufficient to render the triode filament incandescent. As before, a positive potential is applied to the grid and the triode filament employed as a grid for thereby effecting electron bombardment of the grid to heat and outgas the same. When the outgassing is completed, as or after the device is sealed off, the current to the filament is raised and the fabricating filament "burnt out" after which filament

currents applied will be effective upon the triode filament only.

By either embodiment of the invention, it will now be apparent that the triode grid may be outgassed with a high voltage low current bombardment but without subjecting the triode filament to ion bombardment during exhaust. It will also be observed that the construction and method described enables the grid to have reenforcing wires as part thereof without interfering with the outgassing operation. Likewise, in both constructions, the fabricating filament is rendered ineffective by circuit interruption and thereafter the triode electrodes function in their normal capacities.

Since the various details of construction, as well as the precise relation and functioning of parts are subject to variation and change without departing from the inventive concept or scope of the invention, it is intended that all matter contained in the specification or illustrated in the drawing, shall be interpreted as exemplary and not in a limiting sense. It is also to be understood that the following claims are intended to cover all of the generic and specific features of the invention herein shown and described and all statements of the scope of the invention herein set forth as a matter of language which might be said to fall therebetween.

I claim:

1. In an electron discharge device comprising an envelope and triode electrodes, namely, a cathode, grid and anode, the combination of a fabricating filament in addition to and associated with said triode electrodes in such relation therewith that the grid of the triode constitutes an anode with respect to the said fabricating filament.

2. In an electron discharge device comprising an envelope and triode electrodes, namely, a filament, grid and anode, the combination of a fabricating filament in addition to and associated with said triode electrodes in such relation therewith that the filament of the triode constitutes a grid and the grid of the triode constitutes an anode with respect to the said fabricating filament.

3. In an electron discharge device, the combination of triode electrodes, namely, a filament, grid and anode each having a generally cylindrical formation with the triode filament surrounded by parts of the grid and the grid surrounded by parts of the anode, and a fabricating filament surrounded by parts of the cylindrical formation of said triode filament whereby said triode filament may function as a grid with respect to the fabricating filament.

4. In an electron discharge device comprising an envelope and triode electrodes, the combination of a fabricating filament associated with said triode electrodes in such relation therewith that the grid of the triode constitutes an anode with respect to the said fabricating filament, said filaments having means for applying distinct heating currents thereto.

5. In an electron discharge device comprising an envelope and triode electrodes, the combination of a fabricating filament associated with said triode electrodes in such relation therewith that the grid of the triode constitutes an anode with respect to the said fabricating filament, said filaments having a common external connection and each having an independent connection to the other end of each filament for applying distinct heating currents to the two said filaments.

6. In an electron discharge device comprising an envelope and triode electrodes including a filament, the combination of a fabricating filament associated with said triode electrodes in such relation therewith that the grid of the triode constitutes an anode with respect to the said fabricating filament, said filaments being connected in parallel and having common external connections, said fabricating filament having a lower resistance and rendered incandescent with lower current than said triode filament.

7. In an electron discharge device comprising an envelope and triode electrodes including a filament, the combination of a fabricating filament associated with said triode electrodes in such relation therewith that the grid of the triode constitutes an anode with respect to the said fabricating filament, said filaments being connected in parallel and having common external connections, said fabricating filament having a lower resistance and rendered incandescent with lower current than said triode filament and said fabricating filament being incapable of carrying current sufficient to render the triode filament incandescent whereby applying current to render the triode filament incandescent will burn out the fabricating filament.

8. The herein described method of outgassing the triode grid of an electron discharge device comprising utilizing the cathode of the triode as a grid, applying a positive potential to the triode grid, producing an electron discharge through the cathode acting as a grid, and utilizing said triode grid as an anode and obtaining thereby a controlled electron bombardment thereof.

9. The herein described method of outgassing the triode grid of an electron discharge device comprising producing an electron discharge, and rendering said discharge effective upon the triode filament as a grid and upon the triode grid as an anode.

10. The herein described method performed upon and in connection with an electron discharge device having a triode filament, grid and anode and a fabricating filament, comprising rendering the fabricating filament electron emissive and producing an electron discharge effective upon the triode filament as a grid and upon the triode grid as an anode, and thereafter rendering the fabricating filament circuit ineffective and the triode electrodes effective for normal use.

11. The herein described method of outgassing the triode grid of an electron discharge device, comprising supplying a cylindrical cathode, grid and anode to constitute said triode, supplying a stem within the cathode, supplying a fabricating filament around the stem and securing it thereto, producing an electron discharge from the fabricating filament effective upon the triode filament as a grid and upon the triode grid as an anode.

12. A method performed upon and in connection with an electron discharge device wherein said electron discharge device provides an envelope and triode electrodes, namely a cathode, grid and anode and provides an auxiliary source of electrons, said method comprising passing electrons from said auxiliary source in proximity to the said cathode, utilizing said cathode as a grid and thereby controlling the electrons passing in proximity thereto from the said auxiliary source, and utilizing the grid of the electron discharge device as an anode and thereby obtaining a con-

trolled electron bombardment of the grid by electrons from said auxiliary source.

13. A method performed upon and in connection with an electron discharge device wherein said electron discharge device provides an envelope enclosing a cathode, grid, anode and an auxiliary source of electrons, said method comprising: applying a potential to the cathode positive with respect to the auxiliary source of electrons, applying a more positive potential to the grid, and passing electrons from the said auxiliary source into proximity to said cathode and thence to the said grid, thereby bombarding said grid by electrons from said auxiliary source under control exerted by the cathode acting as a grid.

14. A method performed upon and in connection with an electron discharge device wherein said electron discharge device provides an envelope enclosing a cathode, grid, anode and a fabricating electron-emitting filament, and with which are provided external connections to said cathode, grid, anode and fabricating filament, said method comprising connecting the fabricating filament to a source of electrical energy thereby causing electrons to emit from said filament, applying a positive potential to the cathode and a more positive potential to the grid through their respective connections, thereby effecting a controlled bombardment of the grid by electrons from the fabricating filament, and thereafter disrupting the circuit of external connection and fabricating filament and rendering the device usable only by electron emission from the cathode.

15. A method performed upon and in connection with an electron discharge device wherein said electron discharge device provides a triode filament, grid and anode and a fabricating electron-emissive filament and circuit therefor, connecting said fabricating filament through said circuit to a source of electrical energy, producing an electron discharge from said fabricating filament effective upon the triode filament as a grid and upon the triode grid as an anode, and thereafter rendering the fabricating filament circuit ineffective and the triode filament, grid and anode effective for normal use.

16. A method performed upon and in connection with an electron discharge device wherein said electron discharge device provides an envelope enclosing triode electrodes, namely, a triode filament, a grid and an anode, and also enclosing a fabricating filament associated with said triode electrode in such relation therewith

that the grid of the triode may constitute an anode with respect to the said fabricating filament, said filaments having a common external connection and each having an independent connection to the other end of each filament for applying distinct heating currents to the two said filaments, said method comprising applying a heating current to the connections for the fabricating filament and heating said fabricating filament causing the same to emit electrons, applying a positive potential to the triode filament and a more positive potential to the triode grid thereby constituting the said triode filament a grid with respect to the fabricating filament and the triode grid an anode with respect to the fabricating filament, and thereafter disrupting external connection to the fabricating filament and requiring electron emission producing current to be applied to the triode filament.

17. A method performed upon and in connection with an electron discharge device wherein said electron discharge device provides an envelope enclosing triode electrodes, namely, a triode filament, a grid and an anode, and also enclosing a fabricating filament associated with said triode electrodes in such relation therewith that the grid of the triode may constitute an anode with respect to the said fabricating filament, said filaments being connected in parallel and having common external connections, said fabricating filament having a lower resistance and rendered incandescent with lower current than said triode filament and said fabricating filament being incapable of carrying current sufficient to render the triode filament incandescent, said method comprising applying a source of current to the common external connections for the two filaments of value within the current-carrying capacity of the fabricating filament and sufficient to render the same incandescent, applying a positive potential to the triode filament and a more positive potential to the triode grid thereby constituting the said triode filament a grid and the triode grid an anode with respect to the fabricating filament, and thereafter increasing the current to the common external connections for the filaments above the current-carrying capacity of the fabricating filament but within the current carrying capacity of the triode filament thereby burning-out the fabricating filament and necessitating the current to thereafter be applied to the triode filament for operation of the device.

HAMPTON JENNINGS DAILEY.
